UNITED STATES PATENT OFFICE

2,398,379

STENCIL PRINTING MACHINE

Leo G. Kenney, Chicago, Ill.

Application January 26, 1945, Serial No. 574,765

17 Claims. (Cl. 101—123)

This invention relates to improvements in stencil printing machines and is more particularly concerned with a machine of this type in which a squeegee is mounted upon a carrier frame for reciprocable movement across the upper side of a silk screen stencil or the like to force a printing ink or paint therethrough onto a sheet of material to be printed.

This invention contemplates the provision of a machine of this type in which the stencil frame is preferably mounted upon one end of the platen for pivotal movement into and out of printing engagement with sheet material disposed upon the upper surface of the platen, and in which the stencil frame may readily be adjusted in parallel spaced relation to the upper surface of the platen for printing sheet material of different thicknesses.

This invention further contemplates the provision of an improved squeegee mounting means whereby the inking and printing action of the squeegee may readily be adjusted by the operator for varying the pressure exerted by the squeegee against the surface of the stencil screen to provide the proper distribution of the ink or paint and to produce the desired penetration of the printing medium through the stencil screen onto the sheet material to be printed.

This invention further contemplates the provision of improved means for pivoting the stencil frame into and out of printing position in timed relation with improved means for reciprocating the squeegee carrier.

This invention further contemplates the provision of a sturdy, relatively lightweight stencil printing machine which may be inexpensively constructed of various forms of standard, metallic, structural sections such as channels, angles, etc., and with a minimum amount of finishing or machine work.

This invention embodies other novel features, details of construction, arrangement and adjustment of parts which are hereinafter set forth in the specification and claims and illustrated in the accompanying drawings wherein:

Fig. 1 is a side elevational view showing a stencil printing machine embodying features of this invention, the several parts of the machine being shown in the positions they occupy at the commencement of the printing operation.

Fig. 2 is a side elevational view of the machine showing the position of the several parts during the inking movement of the squeegee.

Fig. 3 is a sectional view taken along the line 3—3 of Fig. 1.

Fig. 4 is a plan view of the machine.

Fig. 5 is fragmentary detail view showing a gate means provided for moving the squeegee into a vertical plane at the commencement of the printing stroke.

Fig. 6 is a fragmentary sectional view taken along the line 6—6 of Fig. 4, showing the squeegee in printing position.

Fig. 7 is a fragmentary side elevational view, partly in section, illustrating the construction and arrangement of parts of the timing mechanism employed for reciprocating the squeegee carrier in timed relation with the pivotal movement of the stencil frame.

Fig. 8 is a fragmentary sectional view taken along the line 8—8 of Fig. 2.

Fig. 9 is a fragmentary detailed sectional view illustrating the manner in which shims may be provided between the stencil frame and the stencil frame support for adjusting the printing position of the screen with respect to the upper surface of the platen to accommodate sheet material of different thicknesses.

Referring now to the drawings for a better understanding of this invention, the improved stencil printing machine is shown as comprising a frame 9 embodying four vertically disposed members 11 which are connected together by means of upper and lower longitudinal members 12 and 13, respectively, and upper and lower transverse members 14 and 15, respectively. The frame members are preferably formed of angle-iron, and the upper longitudinal members 12 are arranged to serve as tracks for a squeegee carrier 17.

The squeegee carrier is also preferably formed of angle-iron and embodying upright members 18, longitudinal members 19 and transverse members 21. The lower ends of the vertical members 18 are secured together at the sides of the carrier 23 by means of plates 22. Similar angle brackets 23 are provided at each of the four corners of the carrier frame to receive stud journals 24 for carrier wheels 26. The carrier wheels are arranged in pairs at each corner of the carrier for engagement with opposite sides of the horizontally disposed legs of the longitudinally extending angle-iron tracks 12.

A squeegee adjustment bracket 27 formed of angle-iron is pivotally connected at 28 to the squeegee carrier. A squeegee holder 29 is pivotally connected at 31 to the free end of the bracket 27 and has its lower end formed for detachable engagement with a squeegee 32 formed of rubber or other suitable material. The squeegee holder is adapted to be alternately pivoted between a verti-

cal position as shown in Fig. 1 and a horizontal position as shown in Fig. 2. The squeegee 32 is adapted to be held in a horizontal position when the squeegee holder 29 is pivoted to a vertical position.

cal printing position and an inclined inking position, and the alternate positions of the squeegee holder may be adjusted by means of adjustment screws 33 and 34. A pair of stud screws 36 are mounted on the squeegee carrier and extend upwardly through apertures provided in the bracket 27 to receive compression springs 37 which act between adjustable wing nuts 38 and the bracket 27 to yieldably resist upward pivotal movement of the latter.

A platen 41 is mounted in a horizontal position upon the frame members 12 to receive sheet material 42 to be printed. A stencil screen holder support 43 is pivotally connected at 44 to the inner end of the platen 41 to receive a stencil holder 46 which is secured thereto by means of bolts 47. In order to accommodate the machine for printing sheet material of various thicknesses, one or more shims 48 may be interposed between the screen holder 46 and its support 43. The screen holder 46 may be of any suitable construction and of the type now commonly employed for mounting a silk stencil screen 49.

The screen holder 46 is pivoted into and out of printing position by means of a cam 51 which acts against a roller 52 journaled on a lever arm 53. One end of the arm 53 is pivotally connected at 54 to the frame 9 and has its free end connected to an actuating arm 56 by means of a connecting link 57.

The squeegee carrier 17 is adapted to be reciprocated back and forth when the screen holder 46 is in its printed position by means of a lever 58 which has its lower end pivotally connected at 59 to the base of the frame 9 and its free end engaging a cross member 61 secured to and depending from the carrier 17. The lever 58 is provided with an auxiliary arm 62 extending upwardly in spaced relation therewith and pivotally connected thereto at 63. The lever 58 and auxiliary arm 62 are connected intermediate their ends by means of a bolt 64 mounted in brackets 66 and 67. A helical compression spring 68 is mounted on the end of the bolt between the bracket 67 and a nut 69. A crank arm 71 is pivotally connected at its one end to the lever 58 and is formed with a downwardly disposed notch 72 at its free end for detachable engagement with a stud 73 mounted on the rim portion of a gear 74.

The crank gear 74 is secured to a shaft 75 journaled in suitable bearings provided on the frame of the machine, and is driven by a pinion gear 76 secured on a shaft 77 which is also journaled in suitable bearings. The shaft 77 is driven by means of an electric motor 78 through suitable belts or chains 80 and 80a, a pair of driving pulleys 79 and 81 and driven pulleys 82 and 83. If desired, the means thus described for imparting reciprocable movement to the squeegee carrier 17 may be duplicated upon the far side of the machine, as shown in Fig. 3, in order to prevent cocking movement of the squeegee carrier and binding thereof against the rails 12. As these parts are similar in construction and operation to the corresponding parts heretofore described, they are indicated by corresponding members.

The cam 51 is secured to the side of a gear 84 which is secured to a shaft 85 suitably journaled on the frame of the machine. The gear 84 is driven by a gear 86 secured to the shaft 75.

A latch 87 is pivotally connected at 88 to the frame 9 and formed with an upturned portion 89 at its free end for engagement with the free end of the crank arm 71 upon alternate revolutions

of the crank gear 74. A latch arm 91 is pivotally connected at 92 to the frame and has its free end connected to the latch 87 by means of a connecting link 93. A resetting latch bar 94 is suspended for longitudinal movement below a frame member 96 by means of pivot links 97, and is provided with an offset portion 98 for engagement by the lever arm 58 when same is moved to its forward position. The latch bar 94 engages the latch 87 through a connecting link 99.

A pair of pivotally mounted gates 101 are mounted on supporting rails 102 secured to the frame 9 of the machine, and are normally maintained in the position shown in Fig. 4 by means 15 of their respective tension springs 103. Upon forward movement of the squeegee carrier 17 the gates 101 are swung outwardly, as illustrated in Fig. 5, by the side arms 105 provided on the outer ends of the squeegee holder 29. The gates 101 20 return to their closed position upon further movement of the arms 105, and during the return stroke of the squeegee carrier 17 the arms 105 are engaged by the respective gates 101 to move the squeegee holder 29 into its vertically disposed position for printing, as illustrated in Fig. 6.

In the operation of the stencil printing machine thus described, the sheet material 42 is placed on the platen 41 when the stencil screen holder 46 is in its raised position, as indicated in Fig. 1, after which the holder 46 is lowered into engagement with the sheet material by gravity under control of the cam 51. During the downward movement of the stencil holder 46, 35 the stud 73 provided on the crank gear 74 rotates in a counterclockwise direction, as illustrated in Fig. 7, to engage the underside of the crank arm 71. The free end of the crank arm 71 is thus moved upwardly to raise the latch arm 91 which acts through the connecting link 93 to move the latch 87 to its inoperative position. Movement of the latch 87 acts through the connecting link 99 to draw the latch bar 94 rearwardly. Upon further rotational movement of 40 the crank gear 74, the stud 73 engages in the recess 72 of the crank arm 71 and acts to move the crank arm in a forward direction. The crank arm, in turn, acts through the auxiliary lever arm 62 to move the squeegee carrier 17 toward the 45 front end of the machine, as illustrated in Fig. 2, to complete the stencil inking operation.

As the squeegee carrier approaches the forward end of the machine, the arms 105 pass beyond the gates 101 which are then automatically closed by means of their respective springs 103. During the forward movement of the squeegee carrier, the lever arm 58 also engages the offset portion 98 of the latch bar 94 which acts through the connecting link 99 to move the latch 87 to its operative crank arm engaging position. After the stud 73 moves upwardly past the horizontal axis of the crank gear 74, it acts through the crank arm 71 and lever arm 58 to move the squeegee carrier 17 rearwardly. During the rearward movement of the squeegee carrier 17, the gates 101 act to lift the arms 105 of the squeegee holder 29 to pivot the latter into its vertical printing position. At the completion of the printing stroke, the free end of the crank arm 71 is engaged by the latch 87, causing the stud 73 to move downwardly out of the crank arm slot 72 for movement independent of the crank arm. When the squeegee carrier 17 reaches the end of its printing stroke, the cam 51 acts through the

arm 53, connecting link 57 and arm 56 to pivot the screen holder 46 to its open position.

It is an important feature of this invention to provide a stencil printing machine with suitable adjustments which are provided to adapt the machine for use in printing sheet material of various thicknesses. In setting up the machine for printing sheet material of predetermined thickness, shims 48 of suitable thickness are interposed between a stencil holder 46 and its support 43, as illustrated in Fig. 9, in order that the stencil screen 49 will be disposed in parallel relation against the sheet material 42 to be printed when the stencil holder 46 is pivoted downwardly into printing position.

The machine is also adapted for printing sheet material of various lengths by adjusting the positions of the gate members 101 longitudinally along their supporting rails 102. The gates 101 are adjustable by means of bolts 106 interposed in slots 107 provided in the side rails 102. It will be understood that the squeegee holder 29 will remain in its inclined inking position during the initial printing stroke of the squeegee carrier 17 and until the arms 105 engage the gates 101 to set the squeegee holder 29 in its vertical printing position.

The inking and printing positions of the squeegee holder 29 may readily be adjusted by means of the adjustment screws 33 and 34. The amount of force exerted by the squeegee against the material to be printed is determined by the yieldable resistance offered by the compression spring 37 acting downwardly against the pivotally mounted supporting bracket 27. The force exerted by the compression spring 37 may be varied by merely adjusting the wing nuts 38 on their studs 36.

The forward travel of the squeegee carrier 17 may be varied by merely adjusting the nuts 69 on their respective bolts 64 to pivot the arms 62 toward or away from their respective lever arms 58.

It will thus be seen that a stencil printing machine constructed according to the present invention is suitable for use in printing sheet material of various lengths and thicknesses, that the various operating parts of the machine may readily be adjusted to suit the type of material to be printed, and that the machine is of relatively simple and inexpensive construction due to the use of standard structural sections such as angle-iron.

While this invention has been shown in but one form, it is obvious to those skilled in the art that it is not so limited but is susceptible of various changes and modifications without departing from the spirit and scope of the claimed invention.

I claim as my invention:

1. In a stencil printing machine, a frame, a platen supported on said frame, a stencil holder pivotally mounted at one end of said platen for movement into and out of printing engagement therewith, a squeegee carrier mounted for reciprocal movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, and gate means for moving said squeegee holder from its inking position to its printing position.

2. In a stencil printing machine, a frame, a platen supported on said frame, a stencil holder pivotally mounted at one end of said platen for movement into and out of printing engagement therewith, a squeegee carrier mounted for reciprocal movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, gate means for moving said squeegee holder from its inking position to its printing position, and means permitting adjustment of said gate means longitudinally of the frame.

3. In a stencil printing machine, a frame, a platen supported on said frame, a stencil holder pivotally mounted at one end of said platen for movement into and out of printing engagement therewith, a squeegee carrier mounted for reciprocal movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, gate means for moving said squeegee holder from its inking position to its printing position, cam means for actuating said stencil holder, a carrier actuating arm pivotally mounted on said frame, a crank journaled for rotational movement on said frame, and a crank arm having its one end engaging said carrier actuating arm and its other end engageable by said crank upon alternate revolutions of the latter.

4. In a stencil printing machine, a frame, a platen supported on said frame, a stencil holder pivotally mounted at one end of said platen for movement into and out of printing engagement therewith, a squeegee carrier mounted for reciprocal movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, gate means for moving said squeegee holder from its inking position to its printing position, cam means for actuating said stencil holder, a carrier actuating arm pivotally mounted on said frame, a crank journaled for rotational movement on said frame, and a crank arm having its one end engaging said carrier actuating arm and its other end engageable by said crank upon alternate revolutions of the latter, and latch means for engagement with said crank arm upon alternate revolutions of said crank.

5. In a stencil printing machine, a frame, a platen supported on said frame, a stencil holder pivotally mounted at one end of said platen for movement into and out of printing engagement therewith, a squeegee carrier mounted for reciprocal movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, gate means for moving said squeegee holder from its inking position to its printing position, cam means for actuating said stencil holder, a carrier actuat-

ing arm pivotally mounted on said frame, a crank journalled for rotational movement on said frame, a crank arm having its one end engaging said carrier actuating arm and its other end engageable by said crank upon alternate revolutions of the latter, and latch means for engagement with said crank arm upon alternate revolutions of said crank, said latch means being actuated by said crank arm and said carrier actuating arm.

6. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, a squeegee holder pivotally mounted on said squeegee bracket, adjustment screws for controlling the limits of pivotal movement of said squeegee holder relative to said squeegee bracket, a squeegee detachably mounted on the lower end of said squeegee holder, said squeegee holder being pivotally movable between an inking position and a printing position, and gate means for moving said squeegee holder from its inking position to its printing position.

7. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, resilient means provided on said carrier for yieldably resisting pivotal movement of said squeegee bracket away from the platen, a squeegee holder pivotally mounted on said squeegee bracket, adjustment screws for controlling the limits of pivotal movement of said squeegee holder relative to said squeegee bracket, a squeegee detachably mounted on the lower end of said squeegee holder, said squeegee holder being pivotally movable between an inking position and a printing position, and gate means for moving said squeegee holder from its inking position to its printing position.

8. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, resilient means provided on said carrier for yieldably resisting pivotal movement of said squeegee bracket away from the platen, means for varying the force exerted by said resilient means, a squeegee holder pivotally mounted on said squeegee bracket, adjustment screws for controlling the limits of pivotal movement of said squeegee holder relative to said squeegee bracket, a squeegee detachably mounted on the lower end of said squeegee holder, said squeegee holder being pivotally movable between an inking position and a printing position, and gate means for moving said squeegee holder from its inking position to its printing position.

9. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, a squeegee holder pivotally mounted on said squeegee bracket, a squeegee detachably mounted on

the lower end of said squeegee holder, said squeegee holder being pivotally movable between an inking position and a printing position, cam means for actuating said stencil holder, a carrier actuating arm pivotally mounted on said frame, a crank journalled for rotational movement on said frame, and a crank arm having its one end engaging said carrier actuating arm and its other end engageable by said crank upon alternate revolutions of the latter.

10. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, a squeegee holder pivotally mounted on said squeegee bracket, and a squeegee detachably mounted on the lower end of said squeegee holder, said squeegee holder being pivotally movable between an inking position and a printing position.

11. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, gate means for moving said squeegee holder from its inking position to its printing position, cam means for actuating said stencil holder, a carrier actuating arm pivotally mounted on said frame, and a crank arm having its one end engaging said carrier actuating arm and its other end engageable by said crank upon alternate revolutions of the latter, means for driving said cam means and said crank in timed relation.

12. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, gate means for moving said squeegee holder from its inking position to its printing position, cam means for actuating said stencil holder, a carrier actuating arm pivotally mounted on said frame, a crank journalled for rotational movement on said frame, and a crank arm having its one end engaging said carrier actuating arm and its other end engageable by said crank upon alternate revolutions of the latter, and latch means for engagement with said crank arm upon alternate revolutions of said crank, said latch means being moved to its inoperative position by said crank arm and to its operative position by said carrier actuating arm.

13. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, a squeegee holder pivotally mounted on said squeegee bracket, a squeegee detachably mounted on

recable movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, cam means for actuating said stencil holder, a carrier actuating arm pivotally mounted on said frame, a crank journalled for rotational movement on said frame, and a crank arm having its one end engaging said carrier actuating arm and its other end engageable by said crank upon alternate revolutions of the latter, and means provided on said carrier actuating arm for varying the reciprocable travel of said squeegee carrier. 15

14. In a stencil printing machine, a frame, a platen supported on said frame, a stencil holder pivotally mounted at one end of said platen for movement into and out of printing engagement therewith, a squeegee carrier mounted for reciprocable movement on said frame, a squeegee bracket pivotally mounted on said carrier, a squeegee holder pivotally mounted on said squeegee bracket, a squeegee detachably mounted on the lower end of said squeegee holder, said squeegee holder being pivotally movable between an inking position and a printing position, cam means for actuating said stencil holder, a carrier actuating arm pivotally mounted on said frame, a crank journalled for rotational movement on said frame, a crank arm having its one end engaging said carrier actuating arm and its other end engageable by said crank upon alternate revolutions of the latter, means provided on said carrier actuating arm for varying the reciprocable travel of said squeegee carrier, and gate means for pivot-

ing said squeegee holder from its inking position to its printing position.

15. In a stencil printing machine, a frame, side rails provided on said frame, a platen supported on said frame above said side rails, a stencil holder support pivotally connected to the inner end of said platen, a stencil holder detachably mounted on said support, a squeegee carrier provided with rollers disposed to straddle said side rails, and lever means for reciprocating said carrier.

16. In a stencil printing machine, a frame, side rails provided on said frame, a platen supported on said frame above said side rails, a stencil holder support pivotally connected to the inner end of said platen, a stencil holder detachably mounted on said support, a squeegee carrier provided with rollers disposed to straddle said side rails, and lever means for reciprocating said carrier, said lever means comprising an actuating lever pivotally mounted on the frame and having a bifurcated end for engagement with said carrier.

17. In a stencil printing machine, a frame, side rails provided on said frame, a platen supported on said frame above said side rails, a stencil holder support pivotally connected to the inner end of said platen, a stencil holder detachably mounted on said support, a squeegee carrier provided with rollers disposed to straddle said side rails, and lever means for reciprocating said carrier, said lever means comprising an actuating lever pivotally mounted on the frame and having a bifurcated end for engagement with said carrier, and means for adjusting said actuating lever for varying the reciprocable travel of said carrier. 35

LEO G. KENNEY.
